CLOTHESLINE PROP

Ruben J. Kroenke and Frank Fuller, East Detroit,
Mich.

Application November 29, 1938, Serial No. 243,040

1 Claim. (Cl. 248—353)

Our invention relates generally to props for lines, cables, and the like, whether of rope, of bare wire, or of covered wire or the like, and particularly to an arrangement of this character in which means is provided for simply and easily but positively locking the upper end of the prop in non-sliding relation to the line, and an important object of our invention is to provide an inexpensive and practical arrangement of this character.

Other important objects and advantages of our invention will be apparent from a reading of the following description taken in connection with the drawing, wherein for purposes of illustration we have shown a preferred embodiment of our invention.

In the drawing:—

Figure 1 is a general perspective view showing the prop in use for supporting a line.

Figure 2 is an enlarged transverse vertical sectional view taken through the upper part of Figure 1.

Figure 3 is a plan view of the upper end of the prop.

Figure 4 is a plan view of the swingable locking member.

Referring in detail to the drawing, the numeral 5 generally designates the prop or the like which is formed in its upper end with a slot 6 which is slightly tapered and has its wide end opening through the terminal of the top of the prop. A clamping bolt receiving hole 7 is spaced below the slot or notch 6 and is longitudinally aligned therewith. A clamping bolt 8 passes through the opening 7 and also through the opening 9 in the swingable locking member 10, the laterally outward terminal of the opening 9 being squared as indicated by the numeral 11 to non-rotatably accommodate the squared portion 12 on the bolt 8 which is adjacent to the head 13 which engages the outer side of the locking member 10 as shown in Figure 2 of the drawing. A washer 14 engages the outer face of the prop 5 and a wing nut 15 is arranged to bear against this washer when threaded on the bolt. The swingable member 10 has formed in one side thereof the arcuate notch or slot 16 which is concentric with the center of the opening 9 and hence with the axis of the bolt 8 and this notch or slot 16 opens through one edge of the member 10.

When the member 10 is assembled by means of the bolt 8 on the prop 5 with the longitudinal axis of the member 10 aligned with the longitudinal axis of the prop 5, the open end of the arcuate notch 16 will be depressed with respect to

the bottom of the notch 6 in the prop 5, while the inner end of the acute notch 16 will be positioned substantially coincidental with the curved bottom 16 of the notch 6, but slightly downwardly displaced.

When the rope, cable, wire, or the like 17 which the prop is to be used to support, is placed in the notch 6 with the locking member 10 in an open position, that is, tilted to one side, and the locking member then brought toward longitudinal alignment with the prop 5, with the line 17 entered in the notch 16, the completion of the movement of the locking member toward alignment with the prop will result in forceful imprisonment of the line in the notches 6 and 16, so that the line is forcibly gripped so that displacement of the prop in any direction relative to the line is positively prevented while the member 10 is held in the closed position by the tightening of the wing nut 15.

Although we have shown and described herein a preferred embodiment of our invention, it is to be definitely understood that we do not desire to limit the invention thereto, and any change or changes may be made in the structure and arrangement of the parts, within the spirit of the invention and the scope of the subjoined claim.

Having described the invention, what is claimed as new is:

A clothes line prop of the class described comprising a bar-like member bifurcated at its outer end and defining a line seating keeper notch between the furcations, a retention member in the form of a substantially rectangular block, said block functioning as a turn-button and being superimposed upon the bifurcated end portion of the prop, an attachment and pivot bolt passing through the block and the adjacent companion portion of the prop at a point in alignment with and below the crotch of said keeper notch, said bolt being provided with a wing nut for clamping the block in open and closed positions, the retention end portion of said block being provided with a transverse kerf, said kerf being at substantial right angles to said keeper notch and of arcuate form, the kerf opening through one longitudinal edge of the block for reception of the adjacent portion of the line, and being disposed for coaction with the crotch portion of the notch and located in concentric relation with respect to the axis of said bolt, whereby to permit it to swing over the line to securely retain the latter in place in the respective notch and kerf.
